UNITED STATES PATENT OFFICE.

WILLIAM M. EDELIN, OF FALLSTON, MARYLAND.

THILL-COUPING.

SPECIFICATION forming part of Letters Patent No. 423,675, dated March 18, 1890.

Application filed January 14, 1890. Serial No. 336,932. (No model.)

To all whom it may concern:

Be it known that I, WILLIAM M. EDELIN, a citizen of the United States, residing at Fallston, in the county of Harford and State 5 of Maryland, have invented certain new and useful Improvements in Thill-Couplings, of which the following is a specification.

My invention relates to improvements in thill-couplings, the object being to provide a 10 device for attaching either shafts or a tongue to the front axle of vehicles, so as to admit of their quick and convenient attachment and detachment, and also to prevent rattling.

The invention is illustrated in the accompanying drawings, in which—

Figure 1 is a section of the axle and shows a side view of the coupling and thill. Fig. 2 is a top view of the same parts. Fig. 3 is a longitudinal section of that part of the coupling which is clipped to the axle. Fig. 4 is a similar view. Fig. 5 shows two views of the thill-iron. Fig. 6 shows two views of the short metal bar and its two leathers.

The letter A designates the axle, B the usual 25 clip, and C the ear-bar of the thill-coupling, to which the said axle-clip is made fast. This ear-bar has two ears D, each provided on its inner face with a socket-bearing e for the rigid trunnion e' on the thill-iron F. The inner face of each ear D also has a horizontal groove g, leading from the rear of the ear forward to the top of said bearing e. The outer side of the ears have a solid wall h, covering both the said bearing e and groove g. No 35 separate pin or bolt is used, the trunnions e', fixed on the thill-iron, being substituted. By this arrangement, when it is desired to attach a pair of shafts or a pole, it is only necessary to place the thill end having the trunnions 40 in position at the rear of the ears D, so that the head part i of the iron will be between the said two ears, and then draw the thill or shafts forward, and thereby cause the trunnions e' to slide along the horizontal ear-grooves g and drop into the bearings e, which are lower 45 than the groove g. These bearings e are bushed or lined with leather k, and the trunnions e' are seated in these leather bushings. As the

bearings e are lower than the horizontal grooves g, it will be seen that neither a pull 50 forward nor a push backward of the thill-iron F will tend to dislodge the trunnions e'.

To effectively confine the trunnions down in their bearings and to cushion them on top, and thereby keep them from rattling, I use 55 two leather blocks l, which are attached to the ends of a short metal bar m, so as to form a frame of three rectangular sides. This frame is placed in position so that the short metal bar m will be crosswise of the ear-bar 60 C, and each of the leather blocks l will occupy one of the horizontal grooves g, and on top of or above a trunnion e', as shown in Fig. 3. A spring n at the back or rear side of the short metal bar m presses against the clip B, or 65 against a shoulder on the ear-bar C, and keeps the leather blocks l to their position. It will thus be seen that the trunnions e' of the thill-iron are surrounded by leather, and the head part i of the thill-iron is also acted on at the 70 flat sides by the leather l, and therefore cannot rattle.

To detach the shafts from a vehicle, it is only necessary, first, to remove the short metal bar m and its leathers l, and then lift 75 out the trunnions e'.

Having described my invention, I claim—

The improved thill or pole coupling consisting of the combination of the iron F, having at its end trunnions e', an ear-bar having two 80 ears D, each provided on its inner face with a horizontal groove g, and also a trunnion-bearing e lower than the groove, but communicating therewith, and said ears having on their outer side a wall h, covering the bearing 85 and groove, and a short crosswise bar m, having two blocks l, each of which occupies one of the said ear-grooves, with a spring to keep the bar and blocks in position.

In testimony whereof I affix my signature in 90 the presence of two witnesses.

WILLIAM M. EDELIN.
